(57) **CLAIM**

The ornamental design for a hair removal device, as shown and described.

DESCRIPTION

FIG. 1 is a front perspective view of a hair removal device of the present invention showing my new design;
FIG. 2 is a front side elevation view thereof;
FIG. 3 is a back side elevation view thereof;
FIG. 4 is a side elevation view thereof (the other side view is a mirror image of FIG. 4);
FIG. 5 is a top plan view thereof; and,
FIG. 6 is a bottom plan view thereof.
